Mario Maccaferri, Rye, N. Y.

Application May 15, 1947, Serial No. 139,061

Term of patent 14 years

(Cl. D17—6)

To all whom it may concern:

Be it known that I, Mario Maccaferri, a citizen of the United States of America, residing at Rye, New York, in the county of Westchester and State of New York, have invented a new, original, and ornamental Design for Clothespin, of which the following is a specification, reference being had to the accompanying drawing, forming part thereof.

Fig. 1 is a perspective view of a clothespin, showing my new design;

Fig. 2 is a side view;

Fig. 3 is a front view;

Fig. 4 is a section taken on line 4—4 of Fig. 3; and

Fig. 5 is a section taken on line 5—5 of Fig. 3.

I claim:

The ornamental design for a clothespin, substantially as shown.

MARIO MACCAFERRI.
